(57) **CLAIM**

The ornamental design of a bottle brush, as shown and described.

DESCRIPTION

FIG. 1 is a perspective view of a bottle brush showing the new design;

FIG. 2 is a top view of the bottle brush of FIG. 1;

FIG. 3 is a left side view of the bottle brush of FIG. 1;

FIG. 4 is a front view of the bottle brush of FIG. 1;

FIG. 5 is a right side view of the bottle brush of FIG. 1;

FIG. 6 is a rear view of the LED housing of bottle brush; and,

FIG. 7 is a bottom view of the bottle brush of FIG. 1.

The broken lines in the drawings depict portions of the bottle brush that form no part of the claimed design.
